SHEET FEEDING MECHANISM

Sherlie E. Gregory, Aurora, Ill.

Application December 29, 1945, Serial No. 638,257

14 Claims. (Cl. 271—42)

1

This invention relates to improvements in sheet feeding mechanisms and it consists of the matters hereinafter described and more particularly pointed out in the appended claims. The invention is more especially concerned with mechanism capable of use in duplicating machines and printing presses and the like that require the delivery of one sheet of paper or card stock, at a time, from a stack thereof to another mechanism for operations thereon.

One of the objects of the present invention is to provide mechanism for the purpose mentioned, which though simple in construction, is efficient in operation at high speed.

Another object of the invention is to provide mechanism of this kind, which is capable of being adjusted to function accurately upon all sizes and thicknesses of paper or card stock, within its capacity.

A further object of the invention is to provide mechanism for the purpose mentioned that includes sheet engageable means that may be set to engage the lateral margins of the paper sheets or cards where the lint picked up from the handling of the cheaper grades of stock will not accumulate upon the stencil of a duplicating machine in an area that will cause blurring of the print made on long runs.

Again, it is an object of the invention to provide mechanism of this kind which includes parts normally overhanging the stack of sheets and which may be swung into an out-of-the-way position permitting a quick and easy replenishing of the sheets in the stack.

Also, it is a further object of the invention to provide in a mechanism of this kind a simple and novel top sheet engageable finger or brush for moving the same in one direction of the stack of sheets.

The above mentioned objects of the invention, along with others, as well as the advantages thereof will more fully appear as the specification proceeds.

In the drawings:

Fig. 1 is a view in side elevation of a stencil duplicating machine embodying the improved sheet feeding mechanism.

Fig. 2 is a transverse vertical sectional view through a part of the improved sheet feeding mechanism as taken on the line 2—2 and on a scale enlarged over that of Fig. 1.

Fig. 3 is a longitudinal vertical sectional view through a part of the mechanism as taken substantially on the line 3—3 and on the scale of Fig. 2.

2

Fig. 4 is a top plan view of that part of the mechanism appearing in and on the scale of Fig. 3.

Fig. 5 is a perspective view of one of the sheet engageable members embodied in the improved mechanism and which will be referred to in more detail later.

Fig. 6 is a perspective view of another one of the sheet engageable members embodied in the mechanism and which will also be more fully referred to later.

Fig. 7 is a fragmentary top plan view of a top sheet engageable finger or brush embodied in the improved mechanism.

Fig. 8 is a perspective view of a rubber or like strip forming a part of the structure appearing in Fig. 7 and before it is folded and curled upon itself for insertion into another part as appears in Fig. 7, and

Fig. 9 is a detailed transverse vertical sectional view through a part of the mechanism appearing in and as taken on the line 9—9 and on the scale of Fig. 4.

The improved sheet feeding mechanism is herein illustrated and described as embodied in a stencil duplicating machine. However this is to be considered as illustrative only of one of the machines with which the improved mechanism may be used because it may also be embodied in gelatin and spirit duplicators, as well as in printing presses, sealing and other machines that require the delivery of one sheet of paper or card stock at a time from a stack of the same.

In general, the improved mechanism, when embodied in a stencil duplicating machine, is disposed in a position above the stack and is mounted for a forward and rearward reciprocation of the stack for each rotation of the stencil cylinder of the machine. In a part of the rearward movement of the mechanism, certain fingers forming a part of the mechanism, frictionally grip the top sheet of the stack and move the same rearwardly thereof so that its rear margin engages and rides up on laterally spaced inclined surfaces at the rear of the stack. This elevates said margin and disposes its edge against stops on the inclined surfaces, at which time the fingers, before mentioned, release the top sheet. The mechanism further includes a member including a hook, which in the final part of the rearward movement of the mechanism, passes far enough rearwardly of the elevated rear edge of the top sheet, so that as soon as the forward movement of the mechanism starts, the sheet is engaged by the hook and pushed forwardly of the stack and

delivered, from the front end thereof, to the stencil cylinder.

Referring now in detail to that embodiment of the invention illustrated in the drawings and especially to Fig. 1 thereof, the improved sheet feeding mechanism is illustrated as embodied in a stencil duplicating machine, the base of which is indicated as a whole at 10. The flat top 11 of said base forms a support for a stack of sheets 12 disposed between laterally spaced guides 13-13 respectively, which direct the delivery of each sheet to the sheet gripping mechanism (not shown) of a stencil cylinder 14, (see Fig. 1). This cylinder is mounted on a transverse shaft 15 journaled toward one end of the base for rotary movement in the direction indicated by the arrow 16 in Fig. 1.

Along one side of the base is a horizontally disposed bar 17 (see Fig. 1) that is arranged for guided reciprocation in any suitable manner longitudinally of the base. At the front end of said bar 17 is an upright arm 18 having an elongated upright slot 19, in which engages a crank pin 20, carried by a crank disc 21 fixed to the associated end of the shaft 15. In the rotation of the stencil cylinder it is obvious that the crank pin 20 will, through the arm 18, impart a longitudinal reciprocation of the bar 17, forwardly and rearwardly of the base 10 and the stack of sheets 12 thereon, the throw of said bar equalling that of the crank pin 20.

Toward the rear end of the bar 17 there is fixed an upright supporting plate 22 and spaced inwardly therefrom and fixed to the associated side of the base in any suitable manner is an upright track or rail plate 23, of a length greater than the throw of the crank pin 20. The top edge of said plate 23 is formed with a relatively high rear end track surface 24, a front end track surface 25 slightly lower than that of the surface 24, and an intermediate track surface 26 which is lower than the surface 25. The surfaces 24-25 are joined to the ends of the surface 26 by the reversely curved surface portions, best appearing in Figs. 1 and 3.

Fixed in the upper central portion of the plate 22, against turning movement, is one end of a shaft 27 that extends transversely of the flat top 11 of the base in a plane above that of the stack of paper sheets 12 thereon so as to overhang the same. An arm 28 is fixed to said shaft against relative movement adjacent the supporting plate 22. A collar 29 is fixed to the free end of this shaft as appears in Fig. 2 and the purpose of said arm and collar will appear later.

A tubular member or sleeve 30 surrounds that part of the shaft between the arm 28 and collar 29 and is capable of a limited turning movement thereon and on the outer end of said sleeve is a fixed collar 31 that abuts against the collar 29. The collar 29 is internally recessed to enclose a spring 32, one end of which is fixed to the collar 29 and the other end of which is fixed to the sleeve. This spring normally tends to turn said tubular member or sleeve in a clockwise direction, when viewed as in Fig. 3.

Collars 33 and 34 are fixed to said tubular member, one on each side of the median line of the stack of sheets 12 and each collar has an arm 35 and 36 on the bottom side thereof. The arm 35 extends rearwardly and the arm 36 extends forwardly, as best appears in Fig. 4.

37 indicates a blade disposed on said median line, before mentioned, to the rear of the shaft 27. Said blade, at its forward end, includes a pair of

laterally spaced arms 37a-37a and a connecting member 38, the arms being journaled on the member of sleeve 30, and spaced from each of the collars 33-34.

5 39 and 40 respectively, indicate blades, disposed one on each side of the median line, before referred to, to the front of the shaft 27. Each blade is provided at the rear end with an arm 41-42. The arm 41 is journaled on the member 10 30 between the collar 34 and one arm 37a and the arm 42 is also journaled on said member between the collar 33 and the other arm 37a.

With the arrangement described, the collars 33-34, being fixed to the member 30, hold the 15 arms of the blades 37, 39 and 40 against movement longitudinally of, but permits them to turn relatively to said member. A spring 43 surrounds that part of the member 30 between one arm 37a and the collar 34 and the ends of said springs are 20 so extended as to engage parts of the blades 37, 39 and 40 from above, as to urge them to swing downwardly in opposite direction into a stopped engagement with the arms 35 and 36 of the collars 33 and 34. When the blades 37 and 39 and 40 25 respectively are in their normal position, they extend rearwardly and forwardly from the shaft in a substantially horizontal position in engagement with the arms 35-36, being yieldingly held in this position by reason of the spring 43. However, with the arrangement described, said blades 30 mentioned may be manually swung into an out of the way generally upright position, giving full access to the paper sheet stack 12. When said blades are released, the spring 43 returns them 35 to their normal position, shown in Fig. 3.

On the median line of the top wall 11 of the base, toward the rear end thereof is a longitudinal slot 44, a part of which is covered by a thin sheet metal plate 45, disposed under the rear 40 end of the stack, as best appears in Fig. 3. The rear end of said plate, which determines the position of the rear end of the stack 12, is provided with a pair of upwardly and rearwardly inclined arms 46-46 (see Fig. 4), one spaced on each side 45 of the blade 37 and each terminating in a downwardly and forwardly extending hook 47.

The plate 45 carries on its median line, toward its rear end, a bolt 48, which supports a spring 50 washer 49, by means of a nut 50, the washer 49 acting to frictionally engage the bottom surface of the wall 11, as appears in Fig. 3. By this arrangement the plate 45 may be shifted into different positions longitudinally of the wall 11 and be held frictionally in the desired position by 55 the washer 49. Thus this plate may be adjusted or set in that position that will accommodate that size of paper sheet or card to be operated upon.

Mounted on the blade 37 for longitudinal adjustment thereon is a clip 51 that best appears 60 in perspective in Fig. 5. This clip is made of spring strip stock so as to have a relatively tight friction fit on the blade and fixed to the bottom thereof is a yielding spring arm 52. Said arm extends in a rearwardly and downwardly direction and terminates in a forwardly and downwardly extending hook 53, normally disposed in the horizontal plane of the hooks 47 on the arms 46 before mentioned. With the clip having the frictional fit on the blade, as before mentioned, 65 the clip may be slid longitudinally into different positions on the blade, so as to coact with the arms 46-46, when the plate 45 has been adjusted for a certain size of paper sheets or cards that constitute the stack 12.

75 The blade 39 carries a somewhat similar clip

54 that appears in perspective in Fig. 6. This clip includes a body 55 that is engaged with the bottom surface of the blade 39 and in said body is a longitudinal slot 56. By means of a screw 57 or the like, this clip may be adjusted forwardly or rearwardly of the blade and locked in the adjusted position. Said clip includes a downwardly and rearwardly directed arm 58 that leads off from the front end of the body and which terminates in a downwardly and forwardly extending hook 58a, which is used when feeding postcard stock, when the plate 45 has been adjusted forwardly on the wall 11 into proper position for that purpose.

Associated with each blade 39 and 40 is a top sheet frictional gripping member that includes a rod 60 preferably of a rectangular cross section and having an annular head 61 at one end. This head holds a frictional gripping member 62, preferably made from a strip of rubber or the like, such as appears in Fig. 8 and bearing the numeral 62a. Said strip, which has longitudinal corrugations 62b on one face thereof, is plain on the other face. Such a rubber strip is folded transversely, with the corrugations on the outside thereof, to bring end portions of the strip together and which folded rubber strip, which is wider than the diameter of the head 61, is forced thereinto and then permitted to expand into substantially the condition appearing in Fig. 7. This disposes the transversely folded part of the strip below the head 61, and which part tends to bulge and which opens up the corrugations, and forms a number of spaced frictional gripping surfaces for engagement with the top sheet in the stack 12.

Extending through each blade 39—40 from below, is a stud 63 (see Fig. 9) and in the bottom portion of said stud is a longitudinal slot 64, of the width of a rod 60. The upper end of said stud is threaded to receive a thumb nut 65. The rod 60 of each top sheet gripping member is inserted through the slot 64 of its stud 63 from below the associated blade 39 or 40. When a nut 65 is tightened upon its stud, it serves to draw the associated rod 60 into a fixed position relative to the blade. It is obvious that by loosening the nut 65, the rod 60 may be adjusted longitudinally with respect to its stud 63 so as to be of different effective lengths. By swinging the rods 60 laterally and thereby causing the studs 63 to turn in the associated blade 39 or 40, a universal adjustment is afforded for the gripping elements as a whole. The frictional gripping elements 62, as afforded by the rubber strips 62a, may be adjusted into forward and rearward positions, as well as laterally, as appears in Fig. 4, to engage upon that area of the top sheet in the stack, as may be desired. Thus, these frictional gripping elements may be adjusted to function with all standard sizes of paper sheets, half sheets and postcard stock, as are operated upon by the machine. It will be noted that these elements have a considerable adjustment as to "sweep." Therefore, they may be set to engage the top sheet at the lateral margins thereof and when the paper is of the cheaper grade and will slough off lint, this lint will not accumulate on the stencil in the areas that will cause blurring of the produced print on long runs of such paper.

66 indicates a downwardly and forwardly extending arm, which is fixed to the sleeve 30, adjacent the arm 28, and in the bottom edge of the arm 66 is a shoulder 67, adapted for release-

able engagement by a pawl 68 pivoted to the arm 28, as at 69. This pawl has a relatively long heavy rearwardly and downwardly extending tail piece 70, which in the forward movement of the supporting plate 22 is adapted to engage a stud 71, that projects outwardly from the face of the rail plate 23. These parts best appear in Figs. 1, 2 and 3 of the drawings.

72 indicates an arm that is fixed at one end 10 to the sleeve 27 adjacent the arm 66 and which arm extends forwardly and somewhat downwardly from the sleeve, as best appears in Figs. 1 and 3. The other end of the arm 72 carries a roller 73 normally held in yielding operative engagement upon the track surfaces 24—25 and 26, of the rail plate 23 by the action of the spring 32.

The operation of the mechanism, when embodied in a stencil duplicating machine, is as follows: In the rotation of the stencil carrying cylinder 14 in the direction of the arrow 16 (in Fig. 1) the bar 17 is reciprocated in a straight line guided path back and forth longitudinally of the base 10. As the supporting plate 22, and parts mounted on the shaft 27 which it carries, is fixed to the bar 17, it is obvious that a like movement is imparted to shaft 27 and sleeve 30 and parts mounted thereon.

In Fig. 1, the supporting plate 22 is shown in the forward limit of its stroke. At this time the topmost sheet of the stack 12 has been fed or delivered to the cylinder 14 and the tail piece 70 of the pawl 68 will have engaged the stud 71 so that the pawl 68 has been released from its engagement behind the shoulder 67 of the arm 66. Also, at this time, the roller 73 on the arm 72 which is fixed to the sleeve 30 is engaged on the track surface 25. With the parts in this position, the arm 72, which is fixed to the sleeve, holds the sleeve 30 against turning on the shaft 27 under the action of the spring 32 so that the friction fingers 62 as provided by the folded rubber strips 62a are spaced from or disposed above the sheet of paper which is now on the top of the stack 12.

In the rearward movement of the bar 17, the supporting plate 22, which carries the shaft 27 and parts mounted thereon, moves rearwardly therewith. As the roller 73 enters upon the lower intermediate track surface 26, the spring 32 will cause the sleeve 30 to rock clockwise when viewed in Fig. 3 so that the friction fingers 62 will pass into frictional engagement upon a front end portion of what is now the top sheet of the stack. In the continued rearward movement of the plate 22, the top sheet of the stack is fed rearwardly and as its rear edge engages the arms 46—46, the rear margin 12x of the sheet will ride upwardly upon the inclined surfaces of the arms until it engages with the hooks 47—47 thereon.

In this rearward movement of the plate 22, when the roller 73 leaves the track surface 26 and rides up onto the track surface 24 the arm 72 rocks the sleeve 30 counterclockwise when viewed in Fig. 3 to lift the friction fingers 62—62 from the top sheet of the stack. When the roller enters upon said surface, the sleeve 30 will have been turned sufficiently so that where the shoulder 67 of the arm 66 rises to a position wherein the pawl 68, under the action of its tail piece 70, drops in behind said shoulder and locks the shaft against turning movement in the other direction.

Of course, in this rearward movement of the plate 22, the blade 37 and clip 51 thereon also move rearwardly and at the end of the movement

of said plates reach a position slightly to the rear of the elevated rear edge of the top sheet now engaged in the hooks 47-47. The blade 37, by reason of the spring 32, is in such position that the hook 53 is elevated to pass said edge of the sheet.

The bar 17 and plate 22 now start forwardly and the hook 53 of the clip 54 will operatively engage or pick up the rear elevated margin 12x of the top sheet and move or push the same forwardly toward the stencil cylinder 14 which now grips the forward edge of the top sheet and moves it into operating position on the cylinder to receive the impression from the stencil thereon.

In this forward movement of the parts, which is the feeding or delivery movement of the top sheet, the pawl 68 is still engaged with the shoulder 67 of the arm 66 and this, of course, so holds the sleeve 30 against turning that the friction fingers 62-62 are disposed in their out of engagement position with respect to said top sheet. Thus when the top sheet of the stack is being moved forwardly toward the cylinder 14, the fingers 62 move forwardly therewith, while in a position elevated above said top sheet.

When the forward movement of the plate 22 is substantially completed, the tail piece 70 of the pawl 68 engages the stud 71 and this rocks the pawl 68 (clockwise as in Fig. 3) so as to withdraw it from behind the shoulder 67. When this occurs, the roller 73 drops into engagement with the track surface 25. This drop, however, is not sufficient to permit the fingers 62-62 to engage the new top sheet of the stack. When the roller 73 rides down upon the intermediate and lower track surface 26, the friction fingers 62-62 drop into gripping engagement with the top sheet and the feeding cycle of said top sheet repeats itself, as before described.

Assume that the stack 12 is to be composed of postcard stock. Under such conditions the plate 45 is moved forwardly into that position wherein the arms 46 and 46 are disposed in operative position relative to the clip 54 on the blade 39 and the operation proceeds as before described, except hook 58a is the pickup instead of hook 53.

When the stack 12 needs replenishing, the blades 37, 39 and 40 respectively are swung into a substantially upright position wherein they are disposed out of the way so that additional paper sheets may be placed upon the stack.

By loosening the nuts 65, the friction fingers or pads 62-62 may be moved forward, rearwardly or laterally inwardly or outwardly, so as to be usable with any size of sheet or card within the range of the machine.

It is obvious from the above description that the structure is quite simple and is devoid of gearing, intricate cam and segment features and the like, which soon get out of timing in operation and require frequent servicings. The mechanism is capable of efficient operation at high speed and is quite noiseless in such operation.

While in describing the invention I have referred in detail to the form, arrangement and construction of the parts involved, the same is to be considered only in the illustrative sense and therefore I do not wish to be limited thereto except as may be specifically set forth in the appended claims.

I claim as my invention:

1. Sheet feeding mechanism embodying therein means for supporting a stack of paper sheets, a support arranged above said stack of sheets for reciprocating movement forwardly and rear-

ardly thereof, means movable with said support and operative in the rearward movement thereof to grip the top sheet of the stack and move it rearwardly and then release the same so that its rear margin extends rearwardly of the rear end of the stack, means at said rear end of the stack for elevating said rear margin of said top sheet when in its extended position, and means movable with the support and operative in the forward movement thereof to engage the elevated rear margin of the top sheet for feeding the same forwardly of the stack.

2. Sheet feeding mechanism embodying therein means for supporting a stack of paper sheets, a support arranged above said stack of sheets for reciprocating movement forwardly and rearwardly thereof, inclined means on said support means at the rear end of the stack, means movable with said support and operative in the rearward movement thereof to grip the top sheet of the stack and move it rearwardly and then release the same after the rear margin of said top sheet has engaged and ridden up said inclined means so as to be elevated above and extended beyond the rear end of the stack, and means movable with said support and operative in the forward movement thereof to engage said margin of the top sheet for feeding the same forwardly of the stack.

3. Sheet feeding mechanism embodying therein means for supporting a stack of paper sheets, a support arranged above said stack of sheets for reciprocating movement forwardly and rearwardly thereof, means pivotally mounted on said support and movable therewith and operative in the rearward movement thereof to grip the top sheet of the stack and to move it rearwardly and then release it so that its rear margin extends rearwardly of the rear end of the stack,

means at the rear end of the stack for elevating said rear margin of the top sheet when in its extended position, and means movable with said support and operative in the forward movement thereof to engage the elevated rear margin of the top sheet for feeding the same forwardly of the stack.

4. Sheet feeding mechanism embodying therein means for supporting a stack of paper sheets, a support arranged above said stack of sheets for reciprocating movement forwardly and rearwardly thereof, means pivotally mounted on said support and movable therewith and operative in the rearward movement thereof to grip the top sheet of the stack and to move it rearwardly and then release it so that its rear margin extends rearwardly of the rear end of the stack, means at the rear end of the stack for elevating said rear margin of the top sheet when in its extended position, and other means pivotally mounted on and movable with said support and operative in the forward movement thereof to engage the elevated rear margin of the top sheet for feeding the same forwardly of the stack.

5. Sheet feeding mechanism embodying therein means for supporting a stack of paper sheets, a support arranged above said stack for reciprocating movement forwardly and rearwardly of the stack, means pivotally mounted on and normally extending generally forwardly therefrom, a second means pivotally mounted on and normally extending generally rearwardly therefrom, means mounted on one of said two last mentioned means and operative in the rearward movement of the support to grip the top sheet of the stack and move it rearwardly and then release the same

so that its rear margin extends rearwardly of the rear end of the stack, means at the rear end of the stack for elevating said rear margin of the top sheet when in its extended position, and means also movable with at least one of said two last mentioned means and operative in the forward movement of the support to engage the elevated rear margin of the top sheet for feeding the same forwardly of the stack, said two last mentioned means being swingable from their generally forwardly and rearwardly extending position to a substantially upright position permitting the placing of papers in stack position on said supporting means.

6. Sheet feeding mechanism embodying therein means for supporting a stack of paper sheets, a support arranged at one side of said supporting means and mounted thereon for reciprocating forward and rearward movement, a non-rotative member fixed to said support in a position above and extending transversely of said stack of sheets, means mounted on said non-rotative member for rocking movement, means carried by said last mentioned means and operative in the rearward movement of said support to grip the top sheet of the stack and move it rearwardly thereof and then release the same so that its rear margin extends rearwardly of the rear end of the stack, means at said rear end of the stack for elevating the extended rear margin of the top sheet, and means also carried by said means mounted on said non-rotative member and operative in the forward movement of the support to engage said elevated rear margin of the top sheet for feeding the same forwardly of the stack.

7. Sheet feeding mechanism embodying therein means for supporting a stack of paper sheets, a support arranged at one side of said supporting means and mounted thereon for reciprocating forward and rearward movement, a non-rotative member fixed to said support in a position above and extending transversely of said stack of sheets, means mounted on said non-rotative member and extending forwardly thereof, means carried by said last mentioned means and operative in the rearward movement of the support to grip the top sheet of the stack and move it rearwardly and then release the same so that its rear margin extends rearwardly of the rear end of the stack, means at the rear end of the stack for elevating the extended rear margin of the top sheet, and means carried by said means mounted on said non-rotative member and extending rearwardly thereof and operative in the forward movement of the support to engage the elevated rear margin of the top sheet for feeding the same forwardly of the stack.

8. Sheet feeding mechanism embodying therein means for supporting a stack of paper sheets, a support arranged at one side of said supporting means and mounted thereon for reciprocating forward and rearward movement, a non-rotative member fixed to said support in a position above and extending transversely of said stack of sheets, means pivotally mounted on the non-rotative member and normally extending forwardly therefrom, means carried by said last mentioned means and operative in the rearward movement of said support to grip the top sheet of the stack and move it rearwardly thereof and then release the same so that its rear margin extends rearwardly of the rear end of the stack, means at the rear end of the stack for elevating the extended rear margin of the top sheet, and

means also pivotally mounted on the non-rotative member and extending rearwardly therefrom, and carrying a member which in the forward movement of the support engages the elevated rear margin of the top sheet for feeding the same forwardly of the stack, both of said means that are pivotally mounted on said non-rotative member being capable of swinging upwardly from their normal forwardly and rearwardly extending positions into substantially an upright position providing for the replenishing of the paper sheets of the stack.

9. Sheet feeding mechanism embodying therein means for supporting a stack of paper sheets, a support arranged at one side of said supporting means and mounted thereon for reciprocating forward and rearward movement, a non-rotative shaft fixed to said support in a position above and extending transversely of said stack of sheets, a tubular member mounted on said shaft for a rocking motion, a member turnably mounted on said tubular member and extending forwardly therefrom and carrying means operable in the rearward movement of the support to engage the top sheet of the stack and move it rearwardly and then release it with its rear margin extended beyond the rear end of the stack, means at the rear end of the stack for elevating the extended margin of the top sheet, a second member turnably mounted on said tubular member and extending rearwardly thereof and carrying means operable in the forward movement of the support to engage and feed said top sheet forwardly, means carried by said tubular member and engageable by both of said last mentioned members to limit the downward turning movement thereof to said forwardly and said rearwardly extending positions respectively, spring means for turning said members about the axis of said tubular member in one direction until stopped by said means carried thereby, each of said last mentioned members being yieldably swingable into positions permitting a replenishing of the sheets in the stack.

10. Sheet feeding mechanism embodying therein means for supporting a stack of sheets, means engaged on said supporting means under the stack of sheets and adjustable to different positions on said supporting means, means carried by said last mentioned means providing upwardly and rearwardly inclined surfaces at the rear of the stack, means disposed above the stack and arranged for reciprocating movement forwardly and rearwardly thereof and including parts which in the rearward movement of the last mentioned means grip the top sheet of the stack and moves it rearwardly so that its rear margin rides up said inclined surfaces into a stopped elevated position and then releases said sheet, said means disposed above said stack also including parts operative in the forward movement of the means disposed above the stack to grip the elevated rear margin of said top sheet and move said sheet forwardly of the stack.

11. Sheet feeding mechanism embodying therein means for supporting a stack of sheets, means engaged on said supporting means under the stack and adjustable to different positions on said supporting means, means carried by said last mentioned means providing upwardly and rearwardly inclined surfaces at the rear of the stack that terminate at the top end in a stop, means disposed above the stack and arranged for reciprocating movement forwardly and rearwardly thereof and including parts which in the

rearward movement of the last mentioned means grips the top sheet and moves it rearwardly so that its rear margin rides up said inclined surfaces to engage said stops and then releases the same, said means disposed above the stack also including a hook-like member on its underside operative in the forward movement of said means to engage the elevated rear margin of said top sheet and feed the sheet forwardly in the forward movement of said reciprocating means.

12. Sheet feeding mechanism embodying therein means for supporting a stack of paper sheets, a support arranged at one side of said supporting means and mounted thereon for a reciprocating movement forwardly and rearwardly of the stack, a non-rotative shaft fixed to said support in a position above and extending transversely of the stack of paper sheets, a tubular member mounted on said shaft for a rocking movement, a member turnably mounted on said tubular member and extending forwardly therefrom and carrying friction finger means for engagement with the top sheet of the stack, means fixed to said tubular member and engageable by said turnable member to limit the downward turning movement thereof, a rail arranged at said side of said supporting means, and having surfaces arranged at different elevations, an arm fixed at one end to said tubular member and carrying a part at its other end for operative engagement with said surfaces in the rearward movement of the support for causing said friction finger means to grip the top sheet to move the same rearwardly and to then release said top sheet in a position where its rear margin is spaced from the rear edge of the stack, and means operative in the forward movement of the supporting member for operatively engaging said rear margin of the top sheet for feeding the same forwardly in the forward movement of the supporting member.

13. Sheet feeding mechanism embodying therein means for supporting a stack of paper sheets, a support arranged at one side of said supporting means and mounted thereon for a reciprocating movement forwardly and rearwardly of the stack, a non-rotative shaft fixed to said support in a position above and extending transversely of the stack of paper sheets, a tubular member mounted on said shaft for a rocking movement, a member turnably mounted on said tubular member and extending forwardly therefrom and carrying friction finger means for engagement with the top sheet of the stack, means fixed to said tubular member and engageable by said turnable member to limit the downward turning movement thereof, a rail arranged at said side of said supporting means, and having surfaces arranged at different elevations, an arm fixed at one end to said tubular member and carrying a part at its other end for operative engagement with said surfaces in the rearward movement of the support for causing said friction

finger means to grip the top sheet to move the same rearwardly, means at the rear end of the stack providing an upwardly and rearwardly inclined surface with a stop at the upper end thereof and up which inclined surface the rear margin of said top sheet rides into engagement with said stop, and means operative in the forward movement of the supporting member for operatively engaging the elevated rear margin of the top sheet for feeding the same forwardly in the forward movement of the supporting.

14. Sheet feeding mechanism embodying therein means for supporting a stack of paper sheets, a support arranged at one side of said supporting means and mounted thereon for a reciprocating movement forwardly and rearwardly of the stack, a non-rotative shaft fixed to said support in a position above and extending transversely of the stack of paper sheets, a tubular member mounted on said shaft for a rocking movement, a member turnably mounted on said tubular member and extending forwardly therefrom and carrying friction finger means for engagement with the top sheet of the stack, means fixed to said tubular member and engageable by said turnable member to limit the downward turning movement thereof, a rail arranged at said side of said supporting means, and having surfaces arranged at different elevations, an arm fixed at one end to said tubular member and carrying a part at its other end for operative engagement with said surfaces in the rearward movement of the support for causing said friction finger means to grip the top sheet to move the same rearwardly, means at the rear end of the stack providing an upwardly and rearwardly inclined surface with a stop at the upper end thereof and up which inclined surface the rear margin of said top sheet rides into engagement with said stop, and means including a hook movable with the supporting member and operable in the forward movement thereof to engage the elevated rear margin of the top sheet for feeding the same forward of the stack.

SHERLIE E. GREGORY.

Certificate of Correction

Patent No. 2,436,168.

February 17, 1948.

SHERLIE E. GREGORY

It is hereby certified that error appears in the printed specification of the above numbered patent requiring correction as follows: Column 12, line 11, claim 13, after the word "supporting" and before the period insert the word *member*; and that the said Letters Patent should be read with this correction therein that the same may conform to the record of the case in the Patent Office.

Signed and sealed this 27th day of April, A. D. 1948.

[SEAL]

THOMAS F. MURPHY,
Assistant Commissioner of Patents.
